UNITED STATES PATENT OFFICE.

JOHN H. GARDEN, OF HARTFORD, CONNECTICUT, ASSIGNOR TO UNDERWOOD TYPE-WRITER COMPANY, OF NEW YORK, N. Y., A CORPORATION OF DELAWARE.

TYPE-WRITING MACHINE.

1,016,686.

Specification of Letters Patent.

Patented Feb. 6, 1912.

Application filed June 19, 1911. Serial No. 634,079.

To all whom it may concern:

Be it known that I, JOHN H. GARDEN, a citizen of the United States, residing in Hartford, in the county of Hartford and State of Connecticut, have invented certain new and useful Improvements in Type-Writing Machines, of which the following is a specification.

This invention relates to side gages which are usually provided on the paper shelves of typewriting machines for guiding the side edges of the work sheets as they are inserted at the introductory side of the platen.

The object of my invention is to provide an improved, simplified, and inexpensively manufactured side gage that will not mar the visible portion of the paper shelf, and that can be readily attached to machines already in use, and also readily assembled upon new machines in course of manufacture.

According to this invention, a rail carried on brackets extends along the rear of the paper shelf near its upper end; a carrier is splined on said rail, and the paper gage is pivotally fastened to the carrier, and a spring connects the carrier with the gage to press it against the front portion of the shelf and prevent accidental lifting. Only the lower edge of the gage presses against the shelf, and its underside is out of contact therewith, to prevent marring when the gage is adjusted. A spring bears against the carrier and rail to maintain the gage where adjusted. By reason of forming the device of two portions, viz. a gage portion and a carrier portion, and pivoting these portions together, the device can be readily assembled on the machine, and is particularly adapted for attaching to old machines or those already in use, where, although the paper shelves may be set or sprung at various angles or may have deformities, the pivotal joint allows the gage the necessary freedom to conform to such shelf and its lower edge to press against it.

In the accompanying drawings, Figure 1 is an end elevation, partly in section, of the platen and platen frame of an Underwood typewriting machine, showing these improvements. Fig. 2 is a plan view of Fig. 1, partially broken away. Fig. 3 shows the gage as raised from the paper shelf.

The usual platen 1 is mounted in a platen frame 2, which has a paper shelf 3 at the rear of the platen, and is provided at its upper edge with a rolled rim 4.

An upstanding projection 5 serves as a side gage for the paper sheets, and is bent up from a plate 6 which lies down on the face of the paper shelf and is shifted therealong. A rail 7 is mounted on brackets 8, by means of screws 9, and the brackets are fastened to the platen frame 2 by the screws 10, which are usually employed to secure the stiffening bar 10^a to the platen frame. Said gage is attached to a bracket or carrier 11 on rail 7, for adjustment along the shelf 3; the carrier 11 having bent ends 12 to form a yoke with bores 13, whereby it is mounted upon the rail 7. The carrier is splined on said rail, by means of a spring 14, pressing a roller or key 15 into a groove 16 in the rail 7, whereby the carrier 11 can be freely moved along said rail for adjustment of the gage, and maintained against accidental displacement by the pressure of spring 14. Ears 17 on carrier 11 carry a rock shaft 18 to which is fastened the gage 5, the plate 6 thereof curving over the rolled rim 4 and extending to said rock shaft 18, to which it is attached by its ears 19. A spring 21, having one end fastened to ear 17, and coiled around rock shaft 18, presses with its other end against the edge 20 of plate 6, and thereby maintains the gage against the shelf 3; the gage being so disposed that only its lower edge 21 presses against the shelf, while the underside of the gage is not in contact therewith, as shown in Fig. 1, so that the visible part of the shelf cannot be marred or scratched when the gage is adjusted therealong.

It will be evident that the gage can be readily assembled on old machines, for after brackets 8 have been fastened to the platen frame, the pivotal joint at 18 affords the necessary freedom for the gage to pass over the rim 4, as shown in Fig. 3, and also allows the plate 6 to conform to the shelf 3 and its edge 21 to press thereagainst, even though the shelves of older machines be set at different angles or even if they have some deformities.

Having thus described my invention, I claim:

1. In a typewriting machine, the combi-

nation with a platen and a paper shelf at the introductory side thereof, of a rod on said shelf, a carrier splined on said rod, a gage hinged to said carrier, and a spring 5 pressing said gage against the shelf.

2. In a typewriting machine, the combination with a platen and a paper shelf at the introductory side thereof, of a rail extending along said shelf, a carrier mounted 10 to travel on said rail to permit adjustment therealong and being secured against transverse movement, means to hold the carrier yieldingly against said rail to prevent accidental displacement, a gage secured pivotally to said carrier, and a spring pressing 15 said gage against the shelf.

3. In a typewriting machine, the combination with a platen and a paper shelf at the introductory side thereof, of a rail extending 20 along said shelf, a carrier mounted to travel on said rail to permit adjustment therealong, a gage secured pivotally to said carrier, and a spring pressing said gage against the shelf; the under side of said 25 gage being out of contact with said shelf.

4. In a typewriting machine, the combination with a platen and a paper shelf at the introductory side thereof, of a rail extending along said shelf, a carrier mounted 30 to travel on said rail, and a gage secured pivotally to said carrier to adapt it to proper disposition on the shelf.

5. In a typewriting machine, the combination with a platen and a paper shelf at the introductory side thereof, of a rail extending 35 along said shelf, a carrier mounted to travel on said rail, a gage secured pivotally to said carrier to adapt it to proper disposition on the shelf, and a spring press-

ing said gage against the shelf to prevent 40 accidental lifting or displacement.

6. In a typewriting machine, the combination with a platen and a paper shelf at the introductory side thereof, of a rail extending 45 along said shelf, a carrier mounted to travel on said rail, and a gage secured pivotally to said carrier to adapt it to proper disposition on the shelf and to facilitate attachment of said parts to the paper shelf.

7. In a typewriting machine, the combination with a platen and a paper shelf at the introductory side thereof, of a rail extending 50 along said shelf, a carrier mounted to travel on said rail, a gage secured pivotally to said carrier to adapt it to proper 55 disposition on the shelf, and a spring connecting said carrier with said gage for pressing the gage against the shelf.

8. In a typewriting machine, the combination with a platen, and a paper shelf at the introductory side thereof, of a carrier 60 mounted at the rear of said shelf and adapted to travel therealong, and a gage secured pivotally to said carrier to adapt it to proper disposition on the shelf.

9. In a typewriting machine, the combination with a platen and a paper shelf at the introductory side thereof, of a carrier mounted at the rear of said shelf and adapted to travel therealong, a gage secured pivotally to said carrier to adapt it to proper disposition on the shelf, and a spring pressing 65 said gage against said shelf to prevent accidental lifting or displacement.

JOHN H. GARDSEN.
